UNITED STATES PATENT OFFICE.

STEPHEN F. GATES, OF BOSTON, MASSACHUSETTS.

IMPROVED ROCK-DRILL.

Specification forming part of Letters Patent No. 55,277, dated June 5, 1866.

To all whom it may concern:

Be it known that I, STEPHEN F. GATES, of Boston, in the county of Suffolk and State of Massachusetts, have invented an Improved Rock-Drill; and I do hereby declare that the following, taken in connection with the drawings which accompany and form part of this specification, is a description of my invention sufficient to enable those skilled in the art to practice it.

In drilling rock, especially when making use of mechanism to actuate the drill, it is found very difficult to obtain a truly cylindrical hole. It is not necessary to elaborate or state the reasons for this, or the theory governing this action of stone-drills, as the fact is well known to quarry and other practical men, the ordinary two-bladed or straight-cut drill tending to make a three-sided hole, and the four-bladed or cross-cut drill tending to form a five-sided hole. The Z-drill is less liable to the objections named than are drills with radial blades equiangular from the center, but it is expensive in construction and difficult to repair.

The object of my invention is the production of round holes by rock-drills of simple and inexpensive formation, my invention consisting in irregularizing the cutters of drills which radiate from a center, so that the spacing on the periphery of the drill from cutter to cutter shall lack uniformity. It is not necessary to give the reason why a drill thus irregularized

will form, in action, a cylindrical hole, as it is proved in practice that round holes are the result of the action of such irregularized drills, and that irregular or angular holes are the result, in stone-drilling, of the action of drills formed with regularly-spaced radial cutters.

Figure 1 of the drawings shows, in side elevation, one of my improved rock-drills having four blades, and Fig. 2 shows a view of the cutting end thereof.

In Fig. 2 it will be seen that two of the blades are left with their cutting-edges in the lines of radii at right angles to each other, while the two others are bent toward each other from such right-angled position, so that of the angles inclosed by the cutting-blades one is a right angle, one an acute angle, and the two others are obtuse angles. While in said illustration the cutters or edges made irregular are those nearest each other, the result would be the same if the opposite edges or cutters were the ones bent or swerved, and they might be thus bent or swerved to either side.

I claim—

A rock-drill when made with cutting-edges arranged substantially as and for the purpose specified.

STEPHEN F. GATES.
